Primary Examiner — Melanie H Tung*Assistant Examiner* — Darmawan Truong(74) *Attorney, Agent, or Firm* — Bose McKinney & Evans LLP(57) **CLAIM**

The ornamental design for a portion of a display screen with a graphical user interface, as shown and described.

DESCRIPTION

The single view is a front view of a portion of a display screen with a graphical user interface.

The broken lines showing a portion of the display screen form no part of the claimed design. The remaining broken lines showing text and portions of the graphical user interface form no part of the claimed design.
